COMBINATION VANITY CASE

Filed Nov. 4, 1929

Inventor

Garland G. Odom

By Adam E. Fisher Attorney

UNITED STATES PATENT OFFICE

GARLAND G. ODOM, OF FORT STOCKTON, TEXAS

COMBINATION VANITY CASE

Application filed November 4, 1929. Serial No. 404,622.

This invention relates to combination vanity cases and the main object is to provide a small and neat case which may be used as the usual vanity case or compact and which 5 may also serve as a cigarette case and a receptacle or carrier for a cigarette holder or lighter or both.

Another object is to provide a novel and efficient means whereby the cigarette holder 10 may be positively held in its place in the case when not in use or readily and conveniently removed from the case when it is used.

A further object is to provide a case of 13 this kind in a simple, efficient and durable form.

The foregoing and other objects together with means whereby the same may be carried into effect will best be understood from 20 the following description of the invention taken in connection with the accompanying drawing wherein:

Figure 1 is a side view of a case constructed in accordance with my invention.

25 Figure 2 is a view from the opposite side showing the case open.

Figure 3 is a front edge view of the case closed.

Figure 4 is an end view of the case opened.

30 Figure 5 is an enlarged detail of the cigarette holder catch.

Figure 6 is a side view of a modification of the case adapted for carrying both a cigarette holder and lighter.

35 Figure 7 is an enlarged detail of the cigarette holder retaining catch used in this modified form.

Figure 8 is a detail side view of the cigarette lighter alone.

40 In the embodiment shown in Figures 1 to 5 inclusive the invention comprises a case 1 which includes the two sections 2 and 3 hereinafter referred to as the receptacle and closure sections respectively. These re-

45 ceptacle and closure sections 2 and 3 are hinged together by hinges 4 at one margin and are provided with complementary clasp buttons 5 at their opposite margins to serve as a means for holding the case closed.

60 6 is a flexible handle for carrying the case 1

and 7 is a ribbon to limit the opening of the two sections 2 and 3 to such point that they are substantially at right angles to each other.

The closure section 3 is in the form of a 55 shallow container as shown at 8 and is provided with the conventional spring set and hinged retaining bar 9 by means of which cigarettes 10 when placed in the closure section may be held in place. The receptacle section 2 is also in the form of a shallow container and a mirror 11 is provided in this section near its top. Below the mirror are the conventional pockets 12 and 13 for face powder and rouge or other cosmetics and to one side of these pockets is provided a recess 14 over which a pivoted lever 15 may be extended to hold a tube of lipstick 16 in place as shown.

One side of the receptacle 2 is extended to 70 form a cigarette holder receptacle 16, the closure section 3 when closed against the said receptacle section being adapted to lie flush with the side of this section 16 so that the case as a whole will be of a relatively shallow rectangular form as shown. In this cigarette holder receptacle 16 a bore 75 or recess 17 is provided into which the cigarette holder as 18 may be inserted. In the lower end of the bore 17 an expansion coil 80 spring 19 is seated and provided with a cap plate 20 against which the mouth end of the cigarette holder may rest, the said spring 19 serving to normally urge the said holder outward from the bore 17. An aperture 85

30 is provided through the side 21 of the cigarette holder receptacle 16 extending into communication with the bore 17, the inner portion of this aperture being enlarged to form a spring chamber 22 as shown in Figure 5. A cigarette holder retaining catch 23 is provided, the same comprising a stem 24 slidably mounted through the aperture 20 and having a knob 25 at its outer extremity.

The inner end 26 of the stem 24 is adapted to be retractably extended into the bore 17 and a fixed collar 27 is provided adjacent this inner end, the said collar 27 being adapted to play in the spring chambers 22. An expansion coil spring 28 is braced be- 90

95 100

tween this collar 27 and the outer end of the chamber 29 and serves to normally urge the catch 23 inward so that the inner end 26 of its stem 24 will engage the upper end of the cigarette holder 18 and so hold it in place against the outward pressure of the spring 19.

The advantages and utility of this device will be evident. It provides a convenient and neat receptacle for face powder and other cosmetics as well as cigarettes and a cigarette holder. The cigarette holder may easily be removed from the case by simply pulling outward on the knob 25 whereupon the spring 19 will eject the holder into the hand. To add to the attractiveness of the case it may be provided with panels 29 of any suitable material such as celluloid or bone fixed to its sides.

20 The embodiment shown in Figures 6, 7 and 8 comprises a case 31 which includes receptacle and closure sections 32 and 33 similar to and arranged in the same manner as the hereinbefore described sections 2 and 3 and is also adapted in the same manner for carrying face powder, rouge lipstick and cigarettes in the same manner. To one side of the case 31 is provided the cigarette holder receptacle 34 similar to the aforesaid 30 receptacle having the bore 35 into which the cigarette holder 36 may be inserted as set forth in the description of the first embodiment. A recess 37 is provided in the wall 38 of the receptacle 34 at the top of the case, a partition 39 intervening between this recess 37 and the bore 35. A plunger 40 is slidably passed through this partition and enters a socket 41 in the wall of the recess 37, the said plunger 40 being normally urged 40 inward into the bore 35 by a coil spring 42 braced between the wall of the recess 37 and the fixed collar 43 so that it will engage the upper end of the cigarette holder 36 and hold it in place. A bell crank 44 is 45 journaled on a shaft 45 extended across the recess 37 at right angles to and below the plunger 40 and the upper end of this crank 44 engages a depended lug 46 upon the collar 43. An operating rod 47 is slidably 50 passed through an aperture 48 in the receptacle 34 and is provided with a knob 49 at its outer end, the inner end engaging the lower arm of the bell crank 44. A stop collar 50 adjacent the inner end of the rod 55 47 is adapted to engage the wall of the recess 37 limiting the inward movement of the plunger 40 and the swinging of the bell crank 44 under the influence of the spring 42 as will be understood. It is obvious that 60 by pressing inward upon the knob 49 the plunger 40 will be withdrawn somewhat from the bore 35 releasing the cigarette holder 36. At the other side of the case 31 in this embodiment of the invention a 65 cigarette lighter receptacle 51 is provided,

the same being similar in form to the aforesaid receptacle 34 and being provided with a tapering socket 52 provided with a spiral female thread 53. A cigarette lighter 54 of the conventional striker type is provided, the same having a spiral male thread 55 adapted to engage said female thread 53 to hold the lighter in the socket 52. A small piece of steel 56 is provided upon the side of the receptacle 51 upon which the lighter may be struck and the case 31 is also provided with the ornamental panels 57 similar to the panels 29 of the first construction.

70 While I have herein set forth certain preferred embodiments of my invention it is understood that I may vary from the same in minor structural details not departing from the spirit of the invention and within the scope of the appended claim.

75 I claim:

In a cigarette holder for a cosmetic case, the said case having an elongated holder receiving bore and having also a recess spaced from and extended in axial alignment with the holder receiving bore, a plunger slidably 90 mounted diametrically through the recess and through the wall between the recess and bore, the said plunger being spring-set to normally extend at one end into the bore, a collar fixed on the plunger in the recess, 95 a bell crank fulcrumed in the recess and engaging the collar on the plunger at one end, an operating rod slidably extended into the recess and engaging the other end of the bell crank, and a stop collar secured on 100 the inner end portion of the operating rod to limit the outward movement thereof.

105 In testimony whereof I affix my signature.

GARLAND G. ODOM.
